LOCK, LATCH, AND FASTENER

Reginald Roberts, London, England

Application December 12, 1933, Serial No. 701,947
In New Zealand December 17, 1932

14 Claims. (Cl. 70—91)

This invention concerns improvements in locks, latches, and fasteners, and although the invention is applicable to locks, latches, and fasteners, for many purposes and of many kinds, e. g. 5 tumbler locks and the like, night latches, control locks for doors and windows and the like, switches, and other locks, latches, and fasteners, the invention is more particularly concerned with latches for doors, in which latches the latch bolt 10 is operable from the outside of the door by a key inserted into a rotatable cylinder, mounted in a housing, and adapted to operate tumbler, lever, or like means provided for locking such cylinder against rotation relative to its housing except 15 when the key has been inserted in the cylinder, and in which the latch bolt is operable from the inside of the door by a knob.

Usually such a latch is provided on the inside of the door with a safety catch which can be 20 operated to prevent movement of the latch bolt either to its locking position or from such position.

With a latch of this kind hitherto it has been 25 possible for an intruder to break the glass in a door or to make a hole in the door and to pass his hand through the latter, to release the safety catch (if necessary) and to operate the said knob and withdraw the latch bolt from the staple on the door jamb and so free the door for opening.

In such latches the cylinder into which the 30 lock key is inserted or the said knob has no positive connection with the latch bolt and although either will, on being suitably operated, draw the latch bolt into the latch casing, neither the cylinder nor the knob can prevent the latch bolt 35 being withdrawn from the co-operating staple, as for example by the insertion of a blade of steel between the door and door jamb to press back the latch bolt.

It is one object of this invention to provide 40 an improved form of lock, latch, or fastener, while a further object of this invention is to provide a latch which can be locked if desired in such a manner as to be openable only by a predetermined key. A still further object of this 45 invention is to provide a latch for doors or the like which can be locked from the inside of the door and/or from the outside thereof so as to be releasable only by a predetermined key from the side of the door at which the latch was locked.

50 In order that the invention may be clearly understood and readily carried into practice, I have appended hereto two sheets of drawings, illustrating the same, in which:—

Figure 1 is an elevation of a night latch with 55 the back plate removed,

Figure 2 is an inside elevation of the back plate showing a latch control plate,

Figure 3 is an end view of the parts shown in Figure 2,

Figure 4 is a part cross sectional view of the 5 thumb and finger latch control for the latch shown in Figure 1,

Figure 5 is an end view of the same part,

Figure 6 is a part cross section of an outside cylinder tumbler lock for use with the night 10 latch shown in Figure 1,

Figure 7 is an end view of the same,

Figure 8 shows an alternative locking bar, and

Figure 9 is a part sectional plan of the cylinder 15 tumbler lock and the night latch as fitted to a door.

The latch bolt 1 (Figure 1) has two guide rods 2 to which is secured at the inner ends a one-piece pressure plate 3. The guide rods 2 are loaded by springs 4 pressing against a keeper 20 plate 5 held in position by lugs 6 attached to a housing 7.

A snap catch 8 of the usual type and having 25 knob 8A, Figure 9, is provided with a lug 9 to engage against a lug 10 on latch bolt 1 to hold the latter in a withdrawn or in a locked position as desired.

A thumb and finger latch control knob 11 (Figures 4, 9 and 10) is secured to a control plate 12 and has lugs 13, which are adapted to engage 30 with ears or extension pieces 14 (Figures 1 and 9) on plate 3. This enables the latch bolt 1 to be withdrawn in the usual manner by turning the knob 11 in either direction.

A cover plate 15 (Figures 2, 3 and 9) is secured 35 to the latch housing 7 by a screw 16A passing through a hole 16 and screwing into an extended boss 17 attached to housing 7 in the usual manner.

A control plate 18 is attached to the cover plate 40 15 by a sleeve 19 to which it is riveted and this plate 18 is operable from a tumbler lock to be described.

When the cover plate 15 is in position lugs 20 45 on the plate 18 engage with extension pieces 14A on the plate or member 3.

The knob 11 (Figures 4 and 9) is fitted with a cylinder 21 which has an oval collar 22 at one end and is fitted with a locking bar 23 at the 50 opposite end, which bar is held in position by a keeper plate 24 and screws 25. Between the keeper plate 24 and control plate 12 is fitted a compression spring 26.

The locking bar 23 passes through an aperture 55

12A in control plate 12 and has a sliding fit in the same.

5 The knob 11 is formed so as to take a cylinder or part 21 which is a sliding fit therein, and the knob has an oval recess in the outer end to take a collar 22 on the cylinder 21.

10 The cylinder 21 and knob 11, when both are in the position shown in Figure 4, are bored and fitted with two tumblers each in two parts respectively marked 27 and 27A, 28 and 28A and springs 29. Any predetermined number of tumblers may be used.

15 The cylinder 21 and collar 22 have a keyway 31 cut somewhat as shown in Figure 5.

19 The tumbler lock 31 shown in Figures 6, 7 and 9 comprises a housing 31A provided with a circular flange 32 housed in a distance piece 33 adapted for mounting on a door. Eccentrically in the housing is mounted a cylinder 34, which 20 has a circular collar 35 at the outer end and is fitted with a locking bar 36 at the other end, which bar is held in position by a keep plate 37 and screws 38. The bar 36 consists of a T headed bolt 36A screwed into a square sectioned bar 36 and provided with a lock nut 36B for locking the bolt and bar in proper adjustment to suit the 25 particular thickness of the door to which the device is fitted. Alternatively the bar 36 may be replaced by a one piece bar 36C (Figure 8) made 30 long enough to allow of it being cut to a length to suit the thickness of the door.

35 When the housing 31A and cylinder 34 are in the position as shown in Figure 6 they are bored and fitted with any predetermined number of tumblers 39 and necessary springs 40. These are held in position by a retaining cover plate 41 which is recessed into flange 32 at one end of the housing and secured at the other end to the latter by a screw 42.

40 The cylinder 34 and collar 35 have a keyway 43 somewhat as shown in Figure 7.

45 The lock latch, and a keeper (Figure 9) are fitted to a door 51 and door jamb 51A as shown in Figure 9 while the latch housing has the addition of a right angled flange 44 which is also screwed to the door.

50 The tumbler lock 31 is held in position in the door by screws 45 passing through the door and screwing into lugs 46 and tightening against a plate 47 through which the screws also pass. A compression spring 48 is fitted between the sleeve 19 and keeper plate 37 and the length of the locking bar 36 is determined and adjusted before 55 the latch housing is screwed in place.

55 The operation of a latch such as is shown in Figure 9 is as follows:—

60 With the locking bars 23 and 36 in the positions shown in full lines at Figure 9 the night latch 1 is free to function substantially in the way normal for latches, the latch bolt being capable of retraction by either the knob 11 or by a key rotating the locking bar 36 and the control plate 18. The latch bolt can be locked in a retracted position or in engagement with the staple 49 by 65 means of the catch 8A. Also the door can be pushed or pulled to and is self-latching in the usual way.

70 If a person leaving the house wants to double lock the door, or in other words positively lock the latch bolt against retraction except by a proper key, he, after closing the door and allowing the latch bolt 1 to engage in the staple, inserts his key in the key slot 43 so freeing the cylinder 34 from the tumblers 39 which lock it in its outer position and then presses the cylinder 75

axially inwards against the pressure of spring 48, after which he holds the cylinder in its innermost position (in which flange 35 abuts housing 32) and withdraws his key thus enabling tumblers 39 to lock the cylinder in the inner position in which locking bar 36 occupies the dotted position shown in Figure 9 and positively prevents the retraction of the latch bolt. The latch bolt can now be operated only from the outside of the door and then only by freeing the cylinder 34 by 10 the proper key and allowing the cylinder to return to its outer position after which it can be turned by the key to retract the latch bolt 1 from the staple 49. Until the cylinder has returned to its outer position, operation of knob 11 will 15 not activate the latch bolt.

19 The latch bolt can be positively locked from the inside of the door by pressing (without a key) the cylinder or part 21 inwardly relative to the knob 11 and so causing the locking bar 23 to 20 move into the dotted position shown in Figure 9 to prevent the withdrawal of the latch bolt, the locking bar being secured in this position by the tumblers 27A, 28A, which engage in the cylinder or part 21 with a snap action. To release the 25 cylinder or part 21 for returning to its normal position by the spring 26 the tip of the key for the tumbler lock cylinder 34 is inserted into the keyway 31 to disengage tumblers 27A, 28A from the cylinder or part 21. When the latch bolt is 30 locked by bar 23 from the inside of the door the latter cannot be opened from the outside thereof even by inserting the proper key in the cylinder 34 or by inserting the hand through the door to turn the knob.

35 It is clear of course that the locking bars 23, 36 also serve to transmit rotary movement respectively from the cylinders 21 and 34 to the plates 12 and 18 for withdrawing the catch when desired.

40 The snap cylinder 21 and the locking bar 23 45 and parts connected therewith, possibly slightly modified, could readily and advantageously be applied to fasteners and ignition switches for motor vehicles and such a switch lock could be operable by the key provided for opening the car doors which could be provided if desired with double or snap or such locking latches or locks according to this invention.

45 It will be understood that should the door shown in Figure 9 blow to a closed position it can be 50 opened from the inside as hitherto without a key.

55 A latch according to this invention has all the advantages of the known latches plus the double or positive locking features explained above.

60 The inside double or positive locking device (with which locks, latches or fasteners need not always be fitted) is especially devised to prevent a person breaking a hole through a door and opening the latter by inserting a hand therethrough, i. e. to prevent the door being opened from the inside without the proper key.

65 A latch as shown in the annexed drawings can be withdrawn by a quarter of a revolution of either the knob 11 or the cylinder 34.

70 The plate 3 may have the lugs 58 which can be engaged respectively by the locking bars 23 and 36 when these are in their inner positions to retain the latch bolt in the retracted position so that the members 23 and 24 can either lock positively the bolt in its projecting position or in its withdrawn position.

75 If desired the knob 11 and element 21 could have a full sequence of tumblers similar to the cylinder 34 and its housing 31, and this is in some

instances advantageous and facilitates the key being withdrawn from the element 21.

It will readily be appreciated that the form of a lock or latch or fastening according to this invention may be varied to suit different doors and circumstances without departing from the scope of this invention as set forth in the claims.

What I claim is:—

1. A fastener including a latch bolt, a rotary element for retracting said latch bolt, means for locking said element against rotation, said means being releasable by a key to enable said element to be rotated to retract said latch bolt, said element being movable endwise parallel to the axis of rotation of said element to effect locking of said latch bolt against movement and means for locking said element in the endwise displaced position in which it effects locking of the latch bolt, said means being releasable by a key.
2. A door lock including a lock bolt, a rotatable knob adapted for retracting said lock bolt from the inside of the door, a rotatable cylinder adapted for retracting said bolt from the outside of the door, a housing in which said cylinder is mounted, means for locking said cylinder against rotation relative to said housing, said means being releasable by a key, an axially movable member associated with said knob, a locking member associated with said axially movable member, said locking member in one position preventing retraction of said bolt, and means for locking said axially movable member in the position in which the said locking member prevents retraction of the bolt, said means being releasable by a key.
3. A door lock including a lock bolt, a rotatable knob adapted for retracting said lock bolt from the inside of the door, an axially movable member associated with said knob, a locking member associated with said axially movable member, means, releasable by a key, for locking said locking member in a position preventing retraction of said bolt, a rotatable cylinder adapted for retracting said bolt from the outside of the door, a housing in which said cylinder is mounted, means for locking said cylinder against rotation relative to said housing, said means being releasable by a key, said cylinder being movable axially, a locking member associated with said cylinder, said locking member in one position preventing retraction of said bolt, and means for locking said cylinder in this position, said means being operable by the key provided for freeing said cylinder for rotation.
4. A door lock as claimed in claim 3, including spring means for moving said bolt locking members automatically out of the bolt locking position when said members are released.
5. A door lock including a lock bolt, a rotatable knob adapted for retracting said lock bolt from the inside of the door, an axially movable member associated with said knob, a locking bar associated with said axially movable member, means for adjusting the length of said locking bar, said locking bar in one position of the axially movable member preventing retraction of said lock bolt, means for locking said axially movable member in this position, said means being releasable by a key, a rotatable cylinder adapted for retracting said bolt from the outside of the door, a housing in which said cylinder is mounted, means for locking said cylinder against rotation relative to said housing, said means being releasable by a key, said cylinder being movable axially, a locking bar associated with said cylinder, means for adjusting the length of said locking bar, said locking bar in one position of said cylinder pre-

venting retraction of said lock bolt, and means for locking said cylinder in this position, said means being operable by the key provided for freeing said cylinder for rotation.

6. A door lock including a lock bolt, a rotatable knob adapted for retracting said lock bolt from the inside of the door, an axially movable member associated with said knob, a locking bar associated with said axially movable member, said locking bar in one position of the axially movable member preventing retraction of said lock bolt, means for locking said axially movable member in this position, said means being releasable by a key, a rotatable cylinder adapted for retracting said bolt from the outside of the door, a housing in which said cylinder is mounted, means for locking said cylinder against rotation relative to said housing, said means being releasable by a key, said cylinder being movable axially, a locking bar associated with said cylinder, said locking bar in one position of said cylinder preventing retraction of said lock bolt, means for locking said cylinder in this position, said means being operable by the key provided for freeing said cylinder for rotation, a rotatable control plate for each of said locking bars, each control plate being rotatable with its locking bar but said bar being slidable endwise relative to said plate, a pressure plate associated with the lock bolt, said pressure plate being engageable by either of said control plates to operate said bolt.

7. A fastener including a latch bolt, a rotary element for retracting said latch bolt, a rotary control plate for said rotary element, part of said element being movable endwise parallel to the axis of rotation of said element to effect locking of said latch bolt against movement, said control plate being rotatable with said part which is slidable endwise relative to said plate, a pressure plate associated with the latch bolt, said pressure plate being engageable by said control plate to operate said bolt, and means for locking said part in the endwise displaced position in which it effects locking of the latch bolt, said means being releasable by a key.

8. A door lock including a lock bolt, a rotatable knob adapted for retracting said lock bolt from the inside of the door, an axially movable member associated with said knob, a locking bar associated with said axially movable member, said locking bar in one position of the axially movable member preventing retraction of said lock bolt, tumbler members for locking said axially movable member in this position, said tumbler members being releasable by a key, a rotatable cylinder adapted for retracting said bolt from the outside of the door, a housing in which said cylinder is mounted, said cylinder being movable axially, a locking bar associated with said cylinder, said locking bar in one position of said cylinder preventing retraction of said lock bolt, tumbler members in said housing for locking said cylinder either in a position in which it prevents retraction of the bolt or separately in a position in which the bolt can be retracted, and said tumbler members being releasable, for permitting movement of the cylinder relative to the housing, and from either position, by the insertion of a key in said cylinder.

9. A door lock including a lock bolt, a rotatable knob adapted for retracting said lock bolt from the inside of the door, an axially movable member associated with said knob, a locking bar associated with said axially movable member, said locking bar in one position of the axially movable

member preventing retraction of said lock bolt, tumbler members for locking said axially movable member in this position, said axially movable member having a keyway, and said tumbler members being releasable by the insertion of a key in said keyway, a rotatable cylinder adapted for retracting said bolt from the outside of the door, a housing in which said cylinder is mounted, said cylinder being movable axially, a locking bar associated with said cylinder, said locking bar in one position of said cylinder preventing retraction of said lock bolt, tumbler members in said housing for locking said cylinder either in a position in which it prevents retraction of the bolt or separately in a position in which the bolt can be retracted, said cylinder having a keyway, and said tumbler members being releasable, for permitting movement of the cylinder relative to the housing, and from either position by the insertion of said key in said keyway.

10. A door lock including a lock bolt, a rotatable knob adapted for retracting said lock bolt from the inside of the door, an axially movable member associated with said knob, said movable member being slideable against the action of a spring with a snap action into a locked position, means for locking said axially movable member in this position, a locking member associated with said axially movable member, said locking member preventing retraction of said bolt when the axially movable member is in the locked position, a rotatable cylinder adapted for retracting said bolt from the outside of the door, a housing in which said cylinder is mounted, means for locking said cylinder against rotation relative to said housing, said means being releasable by a key, said cylinder being movable axially, a locking member associated with said cylinder, said locking member in one position preventing retraction of said bolt, and means releasable by the said key, for locking said cylinder in the position in which the locking bar prevents the retraction of the bolt.

11. A door lock including a lock bolt, a rotatable knob adapted for retracting said lock bolt from the inside of the door, an axially movable member associated with said knob, a locking bar associated with said axially movable member, said locking bar in one position of the axially movable member preventing retraction of said lock bolt, tumbler members for locking said axially movable member in the position in which the locking bar prevents retraction of the bolt, said tumbler members being releasable by a key and comprising cylindrical spring pressed pin tumblers, a rotatable cylinder adapted for retracting said bolt from the outside of the door, a housing in which said cylinder is mounted, said cylinder being movable axially, a locking bar associated with said cylinder, said locking bar in one position of said cylinder preventing retraction of said lock bolt, tumbler members in said housing for locking said cylinder either in a position in which the locking bar prevents the retraction of the bolt or separately in a position in which the bolt can be retracted, said housing and said cylinder having alignable holes, spring pressed pin tumblers in said holes, a cover plate on said housing for closing the open outer ends of said holes, and said tumbler members being releasable, for permitting movement of the cylinder relative to the housing, and from either position, by the insertion of a key in said cylinder.

75 12. A door lock including a lock bolt, a rotatable knob adapted for retracting said lock bolt

from the inside of the door, an axially movable member associated with said knob, a locking bar associated with said axially movable member, said locking bar in one position of the axially movable member preventing retraction of said lock bolt, tumbler members for locking said axially movable member in the position in which said locking bar prevents retraction of the bolt, said tumbler members being releasable by a key, a rotatable cylinder adapted for retracting said bolt from the outside of the door, a housing in which said cylinder is mounted, said cylinder being movable axially, a locking bar associated with said cylinder, said locking bar in one position of said cylinder preventing retraction of said lock bolt, tumbler members in said housing for locking said cylinder either in a position in which the bolt cannot be retracted or separately in a position in which the bolt can be retracted, said tumbler members being releasable, for permitting movement of the cylinder relative to the housing, and from either position, by the insertion of a key in said cylinder, a rotatable control plate for each of said locking bars, each control plate being rotatable with its locking bar but said bar being slidable endwise relative to said plate, a pressure plate associated with the lock bolt, said pressure plate being engageable by either of said control plates to operate said bolt.

13. A door lock including a lock bolt, a rotatable knob adapted for retracting said lock bolt from the inside of the door; an axially movable member associated with said knob, a locking bar associated with said axially movable member, said locking bar in one position of the axially movable member preventing retraction of said lock bolt, tumbler members for locking said axially movable member in the position in which said locking bar prevents retraction of the bolt, said tumbler members being releasable by a key, a rotatable cylinder adapted for retracting said bolt from the outside of the door, a housing in which said cylinder is mounted, said cylinder being movable axially, a locking bar associated with said cylinder, said locking bar in one position of said cylinder preventing retraction of said lock bolt, tumbler members in said housing for locking said cylinder either in a position to prevent retraction of the bolt or separately in a position in which the bolt can be retracted, said tumbler members being releasable, for permitting movement of the cylinder relative to the housing, and from either position, by the insertion of a key in said cylinder, either of said locking bars being movable to lock said bolt and the bolt only being unlocked for operation by releasing the tumbler members associated with the locking bar moved originally to lock the bolt.

members in said housing for locking said cylinder either in a position in which said locking bar prevents retraction of the bolt or separately in a position in which the bolt can be retracted, said 5 tumbler members being releasable, for permitting movement of the cylinder relative to the housing, and from either position, by the insertion of a key in said cylinder, a rotatable control plate for each of said locking bars, each control 10 plate being rotatable with its locking bar but said bar being slidable endwise relative to said plate, a pressure plate associated with the lock bolt, said pressure plate being engageable by either of said control plates to operate said bolt, either of said locking bars being movable to prevent retraction of said bolt and the bolt only being unlocked for operation by releasing the tumbler members associated with the locking bar moved originally to lock the bolt. 5

REGINALD ROBERTS. 10
